UNITED STATES PATENT OFFICE.

HENRY FLAD, OF ST. LOUIS, MISSOURI.

ELECTRO-MAGNETIC VALVE AND CONNECTION.

SPECIFICATION forming part of Letters Patent No. 296,549, dated April 8, 1884.

Application filed June 7, 1883. Renewed February 26, 1884. (No model.)

To all whom it may concern:

Be it known that I, HENRY FLAD, of St. Louis, in the county of St. Louis and State of Missouri, have invented certain new and useful Improvements in Electro-Magnetic Valves and Connections; and I do hereby declare the following to be a full, clear, and exact description of the invention, such as will enable others skilled in the art to which it appertains to make and use the same.

This invention relates to electro-magnetic valves and connections for controlling air-brakes on railway-cars.

The application of air-brakes, both of the "compressed-air" and "vacuum" types, to long trains of railway-cars as heretofore practiced has been attended by several disadvantages, which may be briefly stated as follows:

First. The time required for the air to travel from the air pump or reservoir on the engine increases rapidly with the number of cars, and therefore the brakes cannot be operated as promptly as is desirable.

Second. The brakes of the cars are applied successively, those of the car nearest to the air pump or reservoir being applied first, and those on the car at the rear end of the train being applied after the lapse of a considerable period, during which the brakes have been applied to the intermediate cars, one after the other, and during this period the train is subjected to a series of violent shocks, from the fact that the momentum of the cars on which the brakes have not been applied causes such cars to run up against that portion of the train the speed of which has been slackened by the application of the brakes. These shocks follow one another as the cars are successively brought under the control of the brakes, but the first is the most violent, because the remainder of the train runs onto the first car which is checked.

Third. The release of the brakes is delayed from the same cause.

Fourth. Every time the brakes are operated not only the cylinders require to be charged or exhausted, as the case may be, but the whole system of pipes and connecting-hose has to undergo the process either of filling with compressed air or having the air exhausted therefrom, according to the system employed.

The necessity, therefore, has existed of making the air-supply pipes of very small diameter, and the pumps or reservoirs of great capacity, in the attempt to attain a prompt filling or exhaustion of the pipes; but even when such relative proportions are given to the pipes and their source of supply there is another disadvantage arising from the great frictional resistance to the flow of the air through the pipes of small diameter, this resistance causing a considerable delay before the proper condition of compression or vacuum can be re-established after it has been interrupted by the operation of the brakes. These disadvantages result from the fact that the charging or exhaustion of the brake-cylinders and connecting-pipes must be effected entirely through a cock or valve located upon the locomotive, so that the transmission of effect therefrom to the brake-cylinders through the air-pipes necessarily occupies a time proportionate to the length of the pipes and the quantity of air which must be alternately removed from and replaced in such pipes and the cylinders or other chambers in which are located the pistons or diaphragms which are connected with the brake-levers.

It is the object of my invention to overcome these disadvantages as far as possible; and with this end in view my present improvement consists in a novel combination, with a brake-cylinder provided with suitable ports for connecting the same with the main pipes, of a valve arranged in said cylinder for the opening and closing of said ports, and electro-magnetic devices for controlling said valves, all as hereinafter particularly described in connection with the accompanying drawings, and definitely pointed out in the appended claims.

My present improvement is founded on the same general principle as is the subject of another application for patent which I have filed of even date herewith.

Among the air-brakes to which my invention is applicable I will mention, first, brakes of the Mallinckrodt type operated by air, and in which the main pipes and brake-cylinders must be kept normally charged with compressed air, which drives a piston in each cylinder to raise the car-body and hold off the

brakes by means of the bell-crank levers which are connected to the brakes, the air being allowed to escape to allow the car-body to descend and operate the levers to set the brakes; 5 second, compressed-air brakes of the Westinghouse type, in which compressed air is used to drive the pistons directly to set the brakes; and, third, vacuum-brakes, in which the brake-cylinder is kept exhausted on one 10 side of the piston and atmospheric air admitted to the other side, so that the piston will, in one style of such brakes, be caused to normally hold off the brake-blocks and in another form to apply the brakes by atmospheric 15 pressure.

In the accompanying drawings, Figure 1 is a longitudinal section of a brake-cylinder provided with an electro-magnetic valve constructed and arranged according to my invention, a portion of the main or communicating pipe being shown in elevation. Fig. 2 is a 20 rear end view of the cylinder, the communicating pipe being shown in cross-section. Fig. 3 is a section of the cylinder, valve, main pipe, 25 and connections on the line $x-x$ of Fig. 1, the magnet being shown in elevation. Fig. 4 is a section on the line $x'-x'$ of Figs. 1 and 3. Fig. 5 is a section of a cylinder in a plane similar to that of Fig. 3, and illustrating a modified form 30 of external valve for regulating the communication between the cylinder and external air, and a variation of the connection of the communicating pipe with the cylinder.

The letter A designates the cylinder, B its 35 piston, and C the piston-rod, which, on the outside of the cylinder, is to be connected with the brakes through the ordinary intermediate levers or other motion-transmitting devices. Near the rear end of the cylinder, and at diametrically-opposite points thereof, are outwardly-projecting short necks D D', communicating with the interior of the cylinder and covered by caps d d'. Standing diametrically 40 across the cylinder, and within the same, is a tubular valve, E, the opposite ends of which 45 extend into the necks D and D', respectively, said valve having a slight longitudinal play between the caps d and d', and the inner surfaces of said caps being covered by packing- 50 disks e, to form air-tight joints between the caps and the ends of the valve. The valve is supported and properly guided by suitable 55 bearings, f, arranged in the necks D D', surrounding said valve near its opposite ends, and closing the space around said valve at the inner ends of the necks. These bearings carry 60 annular flexible packing-rings g, the inner margins of which lie against the valve and prevent the leakage of air around it to and 65 from the cylinder. Near its lower end the valve E carries an armature, E', preferably of soft iron, the valve passing through said armature, which projects at opposite sides thereof at right angles. Diametrically across the 70 cylinder, at right angles to the valve, is secured a permanent cross-bar, H, which supports an electro-magnet, I, the poles of which

stand on opposite sides of the valve, and are arranged in such proximity to the armature E' that said armature will be attracted by the 70 magnet when its cores are charged by an electric current traversing its helices i i. The magnet is secured to the cross-bar H by means of clamping-caps h, and the bent portion or yoke of the magnet-cores passes through a 75 passage, e', formed through the valve, said passage being sufficiently large to allow the valve to play longitudinally, so that its ends may come in contact alternately with the packing-disks of the caps d and d', it being understood that when one end of the valve is in contact with the packing of one of said caps its other end will be separated from the packing of the other cap by a space sufficient to allow proper ingress and egress of air to and from 80 the valve, which at an intermediate portion of its length is slotted, as shown at s, to provide free communication between its interior and the interior of the cylinder.

The upper neck, D, of the cylinder is connected with the communicating pipe K by means of a small branch pipe, k, for the passage of air, and said communicating pipe is also connected with the cylinder by a short tube, l, which serves as a passage for the electrical conducting-wires w w, which lead from the respective terminals of the helices of the magnet I, and are passed through the communicating pipe K in opposite directions after leaving the cylinder. The tube l is to be 90 filled around the wires with paraffine or similar material, to prevent the passage of air to and from the cylinder.

The communicating pipe K of each car, in addition to its function as an air-pipe, serves 105 also as a conduit for the conducting-wires, and at each end is provided with the usual connecting-hose, in the couplings of which are arranged automatic wire-connecting devices, as described and illustrated in my application 110 for patent for improvement in electric air-brakes, filed of even date herewith; and I will further add that my present improvement is intended to be used in connection with means for establishing a complete electric circuit, 115 and making and breaking the same similar to those described in my said other application.

The neck D' of the cylinder has connected to it a laterally-projecting tube, M, the outer end of which is closed by an elongated cap, M', the side walls of which are slotted, as shown at m. Upon a seat formed in the end of the tube M is arranged a valve, N, against which bears one end of a spring, O, the other end of which bears against a movable plate, p, in the cap M'. Through the end wall of said cap is arranged an adjusting-screw, Q, the top of which bears against the plate p, so that by means of said screw the opening O may be adjusted to bear with more or less force upon the 125 valve N. The object of this valve is to prevent the escape of any more air than it is absolutely necessary should be discharged from the cylinder when my invention is applied to 130

that type of air-brakes in which the cylinder is kept normally charged with compressed air, and is relieved of pressure in order to allow the weight of the car-body to set the brakes, 5 as will be again referred to.

In Fig. 5 is illustrated an external valve adapted for application to cylinders used in any of the systems of air-brakes heretofore referred to, but especially in those in which the 10 cylinder is only either charged or exhausted for the purpose of operating the brakes.

M² in Fig. 5 is a centrally-bored nipple projecting from the sleeve D, and provided with a screw-cap, M³, having lateral openings m³, 15 connecting its interior with the external air. Through the head or end wall of the cap is arranged the screw-shank M⁴ of a conical valve, N⁴, which may be adjusted more or less into the nipple M², for regulating the area of the outer 20 opening thereof.

The conducting-wires w w lead through the communicating pipes in one direction to the locomotive, and there terminate in one contact plate or button of a circuit-closer, and in 25 the other direction to the rear end of the train, where connection is made with a return branch of a circuit, (preferably composed of the rails of the track,) which on the engine is connected with one pole of the battery, the other pole of 30 which is connected with the circuit-closer contact or button, which is arranged to be brought into contact with that to which the pipe wire branch of the circuit is connected.

Having now described the essential details 35 of construction involved in my improvement, I will explain the modes of using the same in connection with the several systems of air-brakes to which I have heretofore referred.

The Mallinckrodt brake is a representative 40 of a class of car-brakes in which the brakes are set or applied to the wheels by the weight of the car-body, which must, therefore, be kept raised when the brakes are to be held off the wheels. When such brakes are operated by air, the cylinders are kept normally 45 charged with compressed air, to drive the pistons in one direction to raise the car-body through bell-crank levers which are connected by the body, and also to the brakes, 50 the communicating pipes being necessarily kept charged also. The charging is effected by the usual means. When the brakes are to be set or applied to the wheels, the air, is allowed to escape, either wholly or partially, 55 from the cylinder—wholly when the train is brought to a full stop, and only partially when simply a slackening of speed is to be effected. It will be understood that when the brakes are off and the cylinder and communicating pipe 60 charged, the lower end of the valve E will rest by gravity upon the packing-disk of the lower cap, d', and the upper end of said valve will be removed from the packing-disk of the upper cap, d. Communication will therefore 65 be open between the pipe and cylinder and closed between the cylinder and external air. To set the brakes the engineer closes the cir-

cuit by means of the circuit-closer on the engine, and the electric current from the battery traverses the circuit including the helices 70 of the magnet I, and the cores of the said magnet, being thus magnetized, attract the armature E' and raise it and the valve E, so that the upper end of the said valve is driven against the packing-disk of the cap d, and communication between the cylinder and communicating pipe is thus cut off. At the same time the lower end of the valve is raised from the packing-disk of cap d' and communication 75 opened from the cylinder to the external air, so that the compressed air is allowed to escape from the cylinder either wholly or partially, as desired. The pressure on the piston being relaxed, the car-body descends and sets the brakes. A brief closing 80 of the circuit will result in a slackening of speed; but if a full stop is to be made the circuit must be kept closed until the desired effect is produced.

In this system of brakes I prefer to use the 90 external valve, M', as shown in Fig. 3, the pressure of the spring O upon the valve being so adjusted that when, by the escape of air, the pressure in the cylinder is sufficiently reduced to allow an empty car-body to descend 95 and apply the brakes, the valve will be forced to its seat and prevent the further escape of air. A restoration of the normal or standard pressure may obviously thus be more quickly 100 effected to take off the brakes than if the entire pressure were removed in applying them.

In those air-brake systems in which compressed air is used to apply the brakes, the communicating pipe should be connected by pipe k' to the lower neck, D', and the upper 105 neck, D, should be adapted for communication with the external air, as shown in Fig. 5. Communication will thus be normally cut off between the pipe and cylinder and open between the latter and the external air. The 110 pipe will be kept normally charged with compressed air, but the cylinder will be discharged. To apply the brakes, the engineer will close the battery-circuit, and the magnet will attract its armature and raise the valve, thus 115 opening communication to the pipe and closing it to the external air. Compressed air will rush into the cylinder from the pipe and drive the piston to set the brakes, either 120 briefly, to effect a simple slackening of speed, or sufficiently to bring the train to a full stop, according to the time the circuit is kept closed. To take off the brakes after they have been set, the circuit must be broken and the valve resumes its normal position, allowing the cylinder to be discharged and the piston to relax 125 its pressure upon the brakes. The passage from the cylinder to the pipe being now closed, the engineer may put his air-pump in motion, or it may automatically operate to restore the standard pressure in the pipe. For this purpose only an additional quantity of compressed air is necessary which will equal 130 a cylinderful for each car, as that is the

quantity allowed to escape. The renewal of pressure may be accomplished at leisure between the times of setting of the brakes.

In vacuum-brake systems the arrangement 5 of the parts will be the same as in those using compressed air to set the brakes. The main pipe will be kept exhausted of air, communication between the pipe and cylinder will be closed by the valve, and communication to 10 the external air opened. When the circuit is closed, the magnet will attract the armature to raise the valve, close the connection to the outer air, and open the passage from the cylinder to the pipe. The tendency to vacuum 15 thus caused on one side of the piston and the atmospheric pressure on the other side will drive the piston to set the brakes. Breaking the circuit will restore the valves to their normal position, and the standard vacuum may 20 be then re-established by the usual apparatus.

When diaphragms are used in vacuum-brakes, the valve and devices for working the same may be located in a short cylinder inserted in a branch pipe leading from the main 25 pipe to the diaphragm-chamber.

It will now be observed that by using the electro-magnetic valve in each cylinder I am enabled to keep a supply of compressed air of 30 efficient tension close to all the cylinders of a train, so that no appreciable time will be lost by the air in traversing the pipes after communication is established between the cylinder and pipe, and closed to the external air by the movement of the valve. So, also, an efficient 35 vacuum may be maintained in the pipe, so that a prompt exhaust of the cylinders occurs simultaneously upon all the cars of the train as soon as the circuit is closed by the engineer. In other words, a short route, almost 40 without resistance, is provided for the transmission of the desired effect from the locomotive to the brakes on all the cars at the same time, and the hereinbefore-enumerated disadvantages of the old modes of applying air- 45 brakes are almost entirely overcome.

Having now fully described my invention and explained the operation thereof, I claim—

1. The combination, with the cylinder provided with suitable ports, of the tubular diametrically-arranged valve, the armature carried by said valve, and the electro-magnet arranged to attract said armature, substantially as described. 50

2. The combination, with the main or communicating pipe and the cylinder having diametrically-opposite ports or passages arranged for communication with the said pipe and the external air, respectively, of the tubular valve arranged to open and close said ports, and having its interior in communication with the interior of the cylinder, the armature carried by said valve, and the electro-magnet arranged to attract said armature, and having its helices arranged for connection in an electric circuit outside of the cylinder, substantially as 65 described. 60

3. The combination, with the cylinder provided with ports arranged for communication with a main pipe and the external air, respectively, and an electro-magnetic valve for controlling said ports, of a supplementary valve for regulating the flow of air from the cylinder when the electro-magnetic valve has opened the passage to the external air, substantially as described. 70

4. The combination, with the cylinder provided with ports arranged for communication with a supply-pipe and the external air, respectively, and an electro-magnetic valve arranged to open and close said ports alternately, of an automatic regulating-valve arranged to close the communication between the cylinder and external air when the pressure in the cylinder falls to a predetermined point after the electro-magnetic valve has opened the port to 85 the external air, substantially as and for the purpose set forth. 75

In testimony whereof I have signed this specification in the presence of two subscribing witnesses.

HENRY FLAD.
